Des. 187,762
Patented Apr. 26, 1960

187,762

SELF-PRIMING PUMP UNIT

Lawrence P. Marks, Milwaukee, Wis., assignor to Romar
Filter Corporation, Milwaukee, Wis., a corporation of
Wisconsin

Application April 10, 1959, Serial No. 55,445

Term of patent 3½ years

(Cl. D65—1)

Fig. 1

Fig. 2

Fig. 3

Fig. 4

Fig. 5

Fig. 6

Fig. 1 is a right side elevational view of a self-priming pump unit showing my new design;

Fig. 2 is a left side elevational view of the pump;

Fig. 3 is a front elevational view of the pump;

Fig. 4 is a rear elevation view of the same;

Fig. 5 is a top plan view; and

Fig. 6 is bottom plan view of the same.

I claim:

The ornamental design for a self-priming pump unit, as shown.
